UNITED STATES PATENT OFFICE.

WALTER C. PATTERSON, OF ONTARIO, CALIFORNIA, ASSIGNOR TO EDISON ELECTRIC APPLIANCE COMPANY, OF CHICAGO, ILLINOIS, A CORPORATION OF NEW YORK.

MOLDING MACHINE.

Application filed November 14, 1927. Serial No. 232,995.

My invention relates to molding machines, more particularly to machines for making molds from sand for use in casting metal parts, and has for its object the provision 5 of a simple and efficient machine for making molds.

My invention is particularly useful in the making of molds for casting small parts, such, for example, as flatiron parts. In the 10 operation of my machine the molds are made from wet sand and removed from the machine, after which they are sprayed and baked.

For a more complete understanding of my 15 invention reference should be had to the accompanying drawings in which Fig. 1 is a perspective view of a molding machine embodying my invention showing a completed mold ready to be removed from the machine; Fig. 2 is a similar view illustrating the removal of the mold; Fig. 3 is an elevation view of a mold; while Fig. 4 is a perspective view showing the assembly of a group of 20 molds ready for casting.

Referring to the drawing, I have shown 25 my invention in one form as applied to the making of sand molds for casting flatiron parts, although obviously my invention has application in the making of molds for various other parts. The pattern 10 is fixed in 30 position and consists of two flatiron sole or bottom plates of the desired configuration mounted on a short pedestal support 11, which in turn is mounted on a metal base member 12. Pivoted on posts 13 and 14, secured to the front side of the base, is a frame member 15 which may be referred to as a 35 "stripper plate". This plate is skeleton in form having a central opening which fits closely around the top of the pedestal 11 to 40 form a sand tight joint therewith and rests on pins 16 secured to the base member 12. Two of the pins are shown in Fig. 2 when in its lowered position. The top surface of this 45 plate is flush with the lower extremity of the pattern 10 and defines the lower face of the mold as it is formed in the machine. This will be apparent from an examination of Figs. 1 and 2. A removable substantially 50 U-shaped frame 17 for supporting the sand mold is placed on the stripper plate 15, a pin 18 being secured to the stripper plate on each side of this member so as to secure it in position laterally on the stripper plate. The 55 front end of the member 17 abuts against the

protuberances on the stripper plate which form its pivoted support. This frame member 17 will be hereinafter referred to as a "flask". Its inner configuration conforms to the configuration of the pattern but is somewhat larger than the pattern so that the sand may be packed in the flask completely around the top and sides of the pattern. 60

A skeleton-like plate member 19 is pivotally secured to the back end of the support 12, one of its pivots being indicated in Fig. 2 by reference numeral 20. This plate is mounted on the upper ends of two arms, the lower ends of which are pivoted to the base. Only 65 one of these arms 21 is shown in the drawing. This plate 19 will be hereinafter referred to as the "strike-off" plate. It is mounted at such height above the base that it may be swung over on to the top of the flask 17, as indicated in Fig. 1, and secured in place in 70 this position by means of a latch 22 cooperating with the stripper plate. Secured to the upright arms carrying the strike-off plate 19 is a member 23 which, when the parts are 75 assembled, closes the back end of the flask 17. This member 23 carries a central protuberance 24 which defines a V-shaped recess in the mold forming a gate for the molten metal. The internal configuration of the strike-off plate 19 conforms with the internal configuration of the flask 17. 80

A framework embracing the base is provided, this framework comprising upright members 25 and 26 on opposite sides of the base which are pivoted at their lower ends (pivots not shown) and are joined together at their tops by crossbars 27 and 28. Mounted on these crossbars is a plate 29, which may be termed a "squeezer plate". This plate has an outside configuration which is complementary with the internal configuration of the strike-off plate 19 and the plate is mounted in such a position that when the supports 25 and 26 are vertical the plate is directly above the strike-off plate. The object of the 90 squeezer plate is to compress the sand in the mold and to effect this the base 12 and parts carried by it are mounted on suitable means whereby the mold may be raised, such as air pressure elevating mechanism 30, controlled by a lever 31. When the mold is raised the squeezer plate is guided into the strike-off plate by means of pins 32 and 32^a on each side of the squeezer plate which fit in apertures in projecting lugs on the stripper 95 plate. 100

110

plate 15. Only one lug with an aperture 33 is shown in the drawing, this aperture receiving the pin 32. It is contemplated that the squeezer plate will have the same thickness 5 as the strike-off plate so that the sand will be compressed to the upper level of the flask 17. Or, in other words, the squeezer plate is arranged to be forced into the strike-off plate for a distance equal to the thickness of the 10 strike-off plate.

As shown, the sand from which the mold is made is contained in a suitable bin 34 having an opening which is on the same level and just behind the strike-off plate 19. A 15 board 35 is provided between the bin and the strike-off plate, this board being tiltable in an upward direction to permit the strike-off plate to be tilted back, as indicated in Fig. 2.

20 In the operation of the machine, a flask 17 is first put in and the parts assembled as previously described and as shown in Fig. 1. The operator then fills the mold with sand 36 from the bin, this sand being quite damp 25 so that it will adhere together when compressed. The surplus sand is removed by passing a straight edge over the top of the strike-off plate. The mold is then raised by means of the air pressure elevator 30 so as 30 to compress the sand by means of the squeezer plate 29 and the mold is then lowered. This period in the making of the mold is illustrated in Fig. 1. The sand mold is then removed by first tilting back the frame and the 35 strike-off plate as indicated in Fig. 2, and then tilting upward and forward the stripper plate to the position shown. A spring latch 37 cooperates with a projection 38 on the hub of the stripper plate to hold it in its raised 40 position, as shown in Fig. 2. The flask with the sand mold is then removed from the stripper plate, after which an empty flask is put in place and the operation repeated.

45 As shown in Fig. 3, the sand mold 39 thus formed is open at one side. The opposite side of the mold, however, forms a smooth surface, and a plurality of molds are stacked together side by side, as indicated in Fig. 4, the back of one mold constituting the front 50 wall of the adjacent mold. The mold at the end is closed by a suitable plate 40 and a similar plate or obstruction, not shown, is provided for closing the opposite end of the channel 41 into which the molten metal is 55 poured. It will be observed that this channel is formed by the series of recesses 41^a in the molds, these recesses being formed by the gate print 24. A suitable protuberance is provided on the top of the stripper plate 60 which forms a recess 42 in each mold through which the molten metal is poured into the two sections 43 and 44.

65 The sand mold can be very readily handled in the supporting flask 17, the flask being always placed in upright positions with the

open end upward. Preferably the sand molds after being removed from the molding machine are first sprayed with a suitable mixture, such as a mixture of graphite, molasses and water. The molds are then assembled as 70 indicated in Fig. 4 on a suitable conveyor (not shown) on which they are passed through an oven where they are baked. I have found that a baking period of one hour at a temperature of 700° F. is satisfactory. Upon emerging 75 from the oven the molten metal is poured into the molds to form the castings. Preferably the castings remain in the molds until they are comparatively cool whereby the castings cool slowly and are relatively soft 80 so that subsequent annealing is not required. Furthermore, since the molds are thoroughly dry and also hot when the molten metal is poured in, the outside of the casting is not chilled as is done with green or wet sand 85 molds.

Preferably the pattern 10 and the squeezer plate 29 are provided with electric heaters built into their interiors whereby they are heated to a sufficient temperature to prevent the sand from sticking to these parts. These heaters are not shown although electric conductors 44 are shown leading to the heaters on the squeezer plate 29.

90 Projections 45 and 46 are provided on the flasks 17 on opposite sides to facilitate handling the molds. Preferably the molds are supported between parallel bars, the projections 45 and 46 resting on the bars. The bars in turn may be mounted on trucks which may 100 be pushed through the furnace during the baking operation.

95 As previously stated, the lever 31 operates a valve which controls the admission of air to the elevating mechanism 30. When the lever is pushed down the valve is opened to admit air. A stop 47 is provided on the frame 26 just below the lever in such position that 105 when the frame is tilted back as shown in Fig. 2, the stop prevents the lever from being depressed to operate the elevating mechanism. The stop thus acts as a safety device to prevent operation of the elevating mechanism until the frame has been swung forward to the proper position.

110 The lever 31 also controls a valve to admit air to two vibrators, one on each side of the elevating mechanism 30. Only one of the vibrators, designated by the reference numeral 48, is shown, this vibrator being supplied with 115 air through a hose 49. The vibrators are secured to the plate 50 on which the base member 12 rests. Their function is to vibrate the mold during the squeezing operation to more thoroughly compact the sand.

120 While I have described my invention as embodied in concrete form and as operating in a specific manner in accordance with the provisions of the patent statutes, it should be understood that I do not limit my invention 125

thereto since various modifications thereof will suggest themselves to those skilled in the art without departing from the spirit of my invention the scope of which is set forth in 5 the annexed claims.

What I claim as new and desire to secure by Letters Patent of the United States, is:—

1. A machine for making sand molds comprising a pattern, a mold frame surrounding 10 said pattern, a movable support for said frame, a second frame movable onto said mold frame having an opening registering with said mold frame, a pressure member fitting in said second frame, and means for relatively 15 moving said pressure member and said second frame to compress the sand in said mold frame.

2. A machine for making sand molds comprising a pattern, a mold frame surrounding 20 said pattern, a pivoted member forming a support for said mold frame, a pivoted frame having an opening registering with the opening in said mold frame, a pressure member fitting in said second pivoted member, and means for relatively moving said 25 pressure member and said second pivoted member to compress the sand.

3. A machine for making sand molds comprising a base, a pattern on said base, a stripper plate pivotally mounted on one side of 30 said base arranged to be lowered around said pattern, a mold frame on said stripper plate surrounding said pattern, a strike-off plate pivoted on said base arranged to be lowered 35 on said mold frame, said strike-off plate having an opening registering with the opening in said mold frame, a pressure plate arranged to fit in said strike-off plate mounted above said strike-off plate, and means for relatively 40 moving said base and said pressure plate so as to force said pressure plate into said stripper plate to compress the sand.

4. A machine for making sand molds comprising a base member, a pattern on said base 45 member, a mold frame surrounding said pattern, a movable support for said frame, a second frame movable onto said mold frame having an opening registering therewith, a pressure member fitting in said second frame, 50 a support for said pressure member above said second frame, and means for elevating said base member to compress the sand.

5. A machine for making sand molds comprising a pattern, a mold frame surrounding 55 said pattern, a pivoted member forming a support for said mold frame, a second pivoted frame resting on said mold frame having an opening registering with the opening in said mold frame, elevating means forming a support 60 for said parts, a pivoted frame above

said elevating means, and a pressure member carried by said frame arranged to enter the opening in said second pivoted member to compress the sand when said elevating means is operated.

65

6. A machine for making sand molds comprising a base, a pedestal on said base, a pattern mounted on said pedestal, a mold frame support closely surrounding said pedestal having its upper surface substantially flush 70 with the lower extremity of said pattern, a pivotal connection between said support and said base, a mold frame on said support surrounding said pattern, a second frame movable onto said mold frame having an opening 75 registering with said mold frame, a pivotal connection between said second frame and said base, and means fitting in said second frame for compressing the sand in said mold frame.

80

7. A machine for making sand molds comprising a base, a pedestal on said base, a pattern mounted on said pedestal, a mold frame support closely surrounding said pedestal having its upper surface substantially flush 85 with the lower extremity of said pattern, a pivotal connection between said support and said base, a mold frame on said support surrounding said pattern, a second frame movable onto said mold frame having an opening 90 registering with said mold frame, a pivotal connection between said second frame and said base, elevating mechanism forming a support for said base, and a pressure member mounted above said frame arranged to enter 95 said second frame to compress the sand in said mold frame when said elevating mechanism is operated.

95

8. A machine for making sand molds comprising a base, a pedestal on said base, a pattern mounted on said pedestal, a mold frame support closely surrounding said pedestal having its upper surface substantially flush 100 with the lower extremity of said pattern, a pivotal connection between said support and said base, a mold frame on said support surrounding said pattern, a second frame movable onto said mold frame having an opening 105 registering with said mold frame, a pivotal connection between said second frame and said base, elevating mechanism forming a support for said base, a frame pivotally movable over said elevating mechanism, and a pressure member carried by said frame arranged to enter said second frame to compress 110 the sand in said mold frame when said elevating mechanism is operated.

105

In witness whereof, I have hereto set my hand this eighth day of November, 1927.

WALTER C. PATTERSON.
